DESIGN FOR A CAMERA

Gordon Brown Scheibell, Millburn, N. J.

Application June 21, 1935, Serial No. 57,362

Term of patent 7 years

To all whom it may concern:

Be it known that I, Gordon Brown Scheibell, a citizen of the United States, residing at Millburn, in the county of Essex and State of New Jersey, have invented a new, original, and ornamental Design for a Camera, of which the following is a specification, reference being had to the accompanying drawing, forming part thereof.

In the drawing Fig. 1 is a perspective view and Fig. 2 is a perspective view in another direction showing my new design for a camera. The distinctive feature of the design resides in a camera casing substantially of the type disclosed by the drawing and having a plurality of contrasting parallel panels as shown.

I claim:

The ornamental design for a camera as shown and described.

GORDON BROWN SCHEIBELL.
